UNITED STATES PATENT OFFICE.

JOHN COOK, OF CHICAGO, ILLINOIS.

WATER-GAGE.

SPECIFICATION forming part of Letters Patent No. 252,648, dated January 24, 1882.

Application filed May 4, 1881. (No model.)

To all whom it may concern:

Be it known that I, JOHN COOK, residing at Chicago, in the county of Cook and State of Illinois, and a citizen of the United States, 5 have invented a new and useful Improvement in Steam-Gages, of which the following is a full description, reference being had to the accompanying drawings, in which—

Figure 1 is a front elevation, showing an 10 ordinary water-gage, with the reflector in position back of the gage-glass; Fig. 2, a front elevation of the reflector detached; Fig. 3, a top or plan view of the reflector.

This invention relates to that class of water-gages for steam engines and boilers consisting 15 of a strong glass tube standing in a vertical position outside of the boiler, communicating at its upper end by means of a stop cock or other connection connected to the boiler with 20 the steam chamber or space for the admission of steam into the glass, and communicating at its lower end by means of a stop-cock or other connection connected to the boiler with the water-space for the admission of water into 25 the glass, the glass being held in position and supported between the upper and lower stop-cock or other connections by suitable stuffing-boxes, or other means to insure a tight joint, and the height of water in the glass tube coinciding 30 with that of the boiler and indicating the depth of water in the boiler, and the fluctuation or rising and falling of the water in the glass tube indicating that the water communication between the tube and boiler is free and 35 clear.

In this class of water-gages as ordinarily constructed and used it is the general practice to place the gage where it can be easily and 40 readily seen, in order to determine the condition of the water; but in some cases it is often-times exceedingly difficult to locate the gage so as to obtain a clear light and a good view of the glass, and in some instances, even where the light is good and the gage in open view, 45 it is impossible at all times to obtain a clear and distinct showing of the height of water in the glass, and even in the best of circumstances, the glass being small, it is exceedingly difficult, if not wholly impossible, at some distance away, 50 to determine the point or line at which the water stands in the glass or see whether it is fluctuating up and down.

The object of this invention is to enable the line or point at which the water stands in the glass and its condition as to fluctuation or rise 55 and fall to be readily observed and determined under any or all of the varying conditions and circumstances above named, or which are liable to occur; and its nature consists in providing a reflector consisting of two reflecting faces or 60 surfaces standing at an angle to each other, and adapted to be placed back of the glass, and bring the glass in front of and between the reflecting surfaces or faces to increase the sight without increasing the size or diameter of the 65 glass, and produce a perfect, clear, and distinct showing of the condition and height of the water.

In the drawings, A A' represent the reflecting faces or surfaces composing the reflector. 70 These surfaces or faces may be made of strips of looking-glass or other material which will act to reflect the light. These strips are set at an angle to each other, with their inner edges meeting and in contact and their outer edges 75 standing apart, to produce a reflector from which the light will be projected forward and in diagonal lines, so as to present an illuminated space equal in size to the distance apart of the outer edges of the reflecting faces or surfaces. 80

B represents the glass tube of the water-gage; C, the stop-cock or connection for the admission of water; D, the stop-cock or connection for the admission of steam; E F, the stuffing-boxes or collars, located respectively 85 on the stop-cocks or connections C D, between which the glass tube is located and held in position; G, the tie-rods for securing the stop-cocks or connections C D together; H I, the plates or disks on the stop-cocks or connections C D, having suitable opening for the 90 passage of the tie-rods.

The several parts represented by the letters B, C, D, E, F, G, H, and I may be of any of the usual and well-known forms of construction for such parts, arranged and operating in the usual manner, the stop-cock or connection C being attached to communicate with the water in the boiler, and the stop-cock or connection D being attached to communicate with 100 the steam in the usual manner.

The reflecting faces or surfaces A A', when made of looking-glass or other fragile material, are to be mounted in a suitable frame or sup-

ported on a suitable backing-plate to prevent them from being broken easily. When made of a material which is not fragile or easily broken they need not be thus supported.

5 This reflector is located back of the glass tube, and corresponds in length to, or nearly to, the length of the tube, and may be secured in position by being fastened to the tie-rods by clips or straps, which can be turned around 10 such rods, or in some other suitable manner; and it may be secured in place by being fastened to some other portion of the gage than the tie-rods; or it may be provided with collars or rings at each end to fit over the ends of the 15 stuffing-boxes E F, in which latter case it could be turned to present the reflecting surfaces or faces in any desired position; or it may be secured in any other suitable manner that will locate it back of the glass tube, so that it can 20 be revolved, if desired, or remain fixed.

This reflector is to be arranged in such relation to the glass tube that the tube will be in front of and between the reflecting surfaces or faces, so that the light from such surfaces or 25 faces will be projected through the tube, and the reflection of the tube will be produced on both reflecting-surfaces, and cause the tube to appear of an equal width with the illuminated space covered by the reflecting surfaces or 30 faces. By this arrangement the size of the tube is apparently increased to the width of the reflecting surfaces or faces, increasing the sight to that extent and presenting an increased area for observation; and by the use of this reflect-

or a more perfect, better, and reliable light is 35 obtained. The light is projected through the tube and its contained water from the back, rendering the tube more transparent and clear. The line or point at which the water stands and its condition will be shown more perfect and distinct, and this line will be projected and appear also on the reflecting surfaces or faces at precisely the same height, so that it can be seen at a considerable distance away with great distinctness and perfect ease, producing a reliable, accurate, and perfect instrument, by which the condition of the water can be perceived at a glance.

I do not broadly claim a reflector arranged in relation to the glass tube of a steam-gage; 50 but

What I claim as new, and desire to secure by Letters Patent, is as follows:

In combination with the glass water-tube of an ordinary steam-gage, the within-described 55 reflector, consisting of two upright reflecting-surfaces arranged at or about right angles to each other, with their inner vertical edges abutting and their outer edges standing apart, to reflect the light in diagonal lines and increase the sight without increasing the diameter of the gage-glass, substantially as described.

JOHN COOK.
